TORQUE TOOL WITH YIELDING DRIVE

John J. Greer, Conimicut, R. I.

Application February 8, 1945, Serial No. 576,827

2 Claims. (Cl. 81—52.4)

1

This invention relates to a torque applying tool, particularly one in which the axis of the work engaging element and the means through which torque is transmitted to the work engaging element are coaxial with each other.

An object of this invention is to provide a tool of this character in which a predetermined torque is applied to the work.

Another object of the invention is to provide a tool of this character in which the amount of torque applied to the work will be indicated.

Another object of the invention is to provide a tool of this character in which the application of torque will be through a yielding force.

Another object of the invention is to provide a tool of this character in which the application of torque will be through a resilient yielding force.

Another object of the invention is to provide a tool of this character in which the application of torque will be through a yielding force which may be controlled so as to provide variable operating values.

With these and other objects in view, the invention consists of certain novel features of construction, as will be more fully described and particularly pointed out in the appended claims.

In the accompanying drawings:

Fig. 1 is a longitudinal central sectional view of a screwdriver embodying the invention;

Fig. 2 is a sectional view of the handle of the screwdriver showing the relative position of several elements secured thereto;

Fig. 3 is a perspective view of an assembly of the elements shown attached to the handle in Fig. 2;

Fig. 4 is a perspective view of a support bearing member;

Fig. 5 is a perspective view of a portion of a spring through which torque is transmitted to the work;

Fig. 6 is a sectional view taken substantially along line 6—6 of Fig. 1;

Fig. 7 is an elevational view of a portion of the handle showing the window through which the torque value graduated scale may be viewed;

Fig. 8 is a top view of the tool with the cover of the handle removed; and

Fig. 9 is a view similar to that shown in Fig. 8 but showing one of the parts as having been rotated one quarter of a revolution.

In carrying out my invention as applied to a screwdriver I rotatably mount the handle and blade relative to each other and provide for the application of a yielding force to oppose relative rotation between the handle and the blade. This

2

opposing force in the instant application is furnished by means of springs which are engaged by the screwdriver blade or some element carried by the blade. When a torque producing force is applied to the handle, both handle and blade will turn as a unit until the torque applied exceeds in the opposing value of the force furnished by the springs. Means are also provided whereby the effective length of the springs may be varied in order that variable values opposing the relative rotation between blade and handle may be had.

Referring to the drawings for a more detailed description of the invention, 15 designates generally a screwdriver having a blade 16 to which is rotatably attached a handle 17. The handle is hollow and is provided at its upper end with a support 18 (see Fig. 4) having a central bearing opening 19 and oppositely disposed guide slots 20 which extend radially inwardly from the periphery of the support. The support 18 is snugly received within the bore 21 and is seated on an annular shoulder 22 and is fastened in place by screw bolts 23. The shank 24 of the blade 16 is journaled in the opening 19 and has a portion 25 thereof extending upwardly beyond the support. This portion 25 is reduced in size providing a shoulder 26 and a non-circular extension which receives a cam member 27 made in the form of an elongated collar. This cam member has an opening to conform to the cross section of part 25 and rests on the shoulder 26. The end extremity of the portion 25 is up-set against the collar 27 and securely fastens the same in place. The lower part of the handle has an annular recess 28 in which is received a thrust ball bearing 29. The outer race 30 of the bearing may be secured to the wall of the recess in any approved manner and the inner race 31 to the shank 24. A collar 32 is secured to the shank by means of a pin 32' and provides an abutment against which the inner race 31 rests.

In order to oppose relative rotation between the handle and blade of the screwdriver, I provide flat springs 33. These are positioned within the handle in a manner such as to be at a location opposite each other and extend lengthwise of the handle through the guide slots 20. The other ends of the springs 33 are anchored in the lower end of the handle by means of a support 34 which rests on the bottom of the hollow of the handle. The support is fastened in place by means of a screw bolt 35 extending through the handle and threadingly engaging the support 34. The support 34 is provided with a square opening 36 (see Fig. 3) which receives the ends of the springs

which are fastened to the walls of the opening by rivet pins 37 (see Fig. 1). The upper extremity of each spring is provided with a pad 38 which engages the cam 27.

As a torque producing force is applied to the handle, for transmission to the work, the handle and blade will turn as a unit until the torque applied exceeds the opposing value of the force furnished by the springs 33. This action may occur in either direction in which the torque is applied. In order that variable opposing values to the relative rotation between handle and blade may be had I provide for varying the effective length of the springs. This is accomplished by means of a collar 39 which has a squared opening 40 which embraces the springs 33, and which is movable lengthwise of the springs. The collar 39 is moved along the springs by means of a threaded member 41 which has a shank portion 42. This shank is journaled in a bearing opening 43 in the support 18. A handle 44 is provided for rotating the member 41 and forms a shoulder 45 with the shank 42. A coiled spring 46 encircles the shank 42 in the space between the shoulder 45 and support 18. A collar 47 is secured to the shank 42 and abuts against the lower surface of the support 18. Thus, the member 41 is mounted for rotation in the opening 43 but is prevented from any substantial relative longitudinal movement therein.

The threaded portion of the member 41 is received in a threaded opening provided in the collar 39. Rotation of the member 41 will move the collar 39 lengthwise of the springs. When the collar is moved towards the free end of the springs the same will be stiffened to offer greater resistance to being spread apart to permit the cam 27 to rotate between the pads 38. When the collar is moved towards the anchored end of the springs the effective length of the springs will be increased and more resiliency will be provided. Consequently, less force will be furnished by the springs on the cam 27 opposing relative rotation between handle and blade. Thus, this arrangement provides for presenting a choice of opposing values against relative movement between handle and blade.

In order to position the collar 39 at the proper location on the springs 33 so as to offer an opposing force of a predetermined value, I provide a scale 48 which is properly graduated as at 49. This scale is fastened in a slot 50 in the collar 39 so as to move therewith. The handle is provided with a window 51 through which the scale may be observed. A datum line 52 is inscribed

on the handle for setting the collar at the proper location by means of the markings on the scale so as to provide an opposing force of the desired value. A cap 53 is telescopically received at the upper end of the handle and completes the assembly of the tool. In some instances the handle may be made of a transparent material and in which case the window 51 may be omitted and the scale observed through the material.

10 I claim:

1. In a torque tool, a work engaging member through which movement is transmitted to the work, a cam secured to said member, a handle rotatably mounted relative to said member and with the axis thereof extending coaxial with the axis of said member, spaced flat springs secured to said handle to move therewith and engaging said cam for opposing relative rotation between said handle and said member but moved apart by said cam under certain pressure to permit relative rotation between handle and member, and a movable collar surrounding and engaging said springs and movable lengthwise thereof for varying the effective length of said springs.
2. In a torque tool, a screwdriver blade, a cam carried by said blade, a handle rotatably mounted relative to said blade, an elongated flexible and resilient member secured to said handle movable therewith and engaging said cam for opposing relative rotation between said handle and blade but flexed by said cam under certain pressure to permit relative rotation between handle and blade, and means movably mounted and engaging said flexible member between the point of engaging said cam and the point fixed to said handle and movable lengthwise relative to said blade and handle along said member for varying the effective length of said flexible member.

JOHN J. GREER.
